UNITED STATES PATENT OFFICE.

CHARLES W. HAWTHORNE, OF BUFFALO, NEW YORK, ASSIGNOR TO MORGAN CONSTRUCTION COMPANY, OF WORCESTER, MASSACHUSETTS, A CORPORATION OF MASSACHUSETTS.

BILLET-HANDLING DEVICE FOR ROLLING-MILLS.

1,308,986.

Specification of Letters Patent.

Patented July 8, 1919.

Continuation in part of application Serial No. 28,317, filed May 15, 1915. This application filed June 27, 1917. Serial No. 177,360.

To all whom it may concern:

Be it known that I, CHARLES W. HAWTHORNE, a citizen of the United States, residing at Buffalo, in the county of Erie and 5 State of New York, have invented a new and useful Improvement in Billet-Handling Devices for Rolling-Mills, of which the following is a specification accompanied by drawings, forming a part of the same, the present 10 application being a continuation in part of my copending application, Serial No. 28,317, filed May 15, 1915.

My present invention relates to billet handling devices for rolling mills, and the objects of the invention are to provide for the rapid and easy withdrawal of billets from the furnace and their introduction into the first stand of rolls, without interference from or difficulty with the coating of scale or 20 oxid formed on the billets during the process of heating; to provide for presenting the billets to the rolls so the scale will be automatically removed by the compression of the rolled metal, and finally to avoid the necessity of using hardened rolls for maintaining 25 the desired dimensions of the rolled metal. These objects, among others, I secure by the construction and arrangement of parts as hereinafter described and illustrated in the 30 accompanying drawings, in which—

Figure 1 is a central longitudinal sectional view of a well known type of a billet heating furnace, and showing a continuous row of billets which are moved by a step-by-step 35 movement to the delivery end of the furnace.

Fig. 2 is a plan view of the delivery end of the furnace shown in section, and in connection with a plan view of a billet ejecting 40 mechanism.

Fig. 3 is a transverse sectional view of the furnace taken on the plane of the side delivery opening, and shown in connection with a side elevation of the billet ejecting 45 mechanism.

Fig. 4 is a transverse sectional view of the trough for supporting the billet ejecting bar on the plane of the broken line 4—4, Fig. 2, said billet ejecting bar being shown in Fig. 2 50 as lying flat upon the bottom of the trough.

Fig. 5 is a transverse sectional view on the

plane of the broken line 5—5, Fig. 2, of the trough for supporting the billet ejecting bar, said billet ejecting bar being represented as having been rotated on its longitudinal 55 axis one eighth of a revolution.

Fig. 6 is a detached view of the inclined plate for protecting the hearth of the furnace and guiding the billet ejecting mechanism.

Fig. 7 is a detached front view of the reducing roll.

Similar reference characters refer to similar parts in the different views.

In the type of furnace shown in the accompanying drawings, the vertical sides of the billets are held in contact, which protects them from the direct action of the heating medium and prevents the formation of scale on these sides of the billet, while the tops of 65 the billets are subjected to the direct action of the heating medium, causing an oxid or scale to be formed on the upper surfaces of the billets. The scale so formed increases in amount until the billets as they approach the 70 delivery end of the furnace become coated with a heavy accumulation of oxid or scale as indicated by the heavy line *a*, Fig. 1. In case the billets are pushed directly from the floor or hearth of the furnace into the reducing rolls, the heavy coating of scale is 75 presented to the surface of the upper roll, and results in impeding the entrance of the billet between the rolls. When the billet has once been entered between the rolls the 80 scale is driven into the soft mass of the heated billet to the detriment of the rolled product.

The effect of the compression of the scale between the metal and the roll has also an 85 injurious effect upon the roll itself, to obviate which it has been customary to harden the surface of the rolls. The operation of hardening the rolls renders it difficult to return the roll passes in order to preserve 90 the desired dimensions and to maintain a smooth rolling surface. In other well known types of heating furnaces the billets are supported upon a raised longitudinal track which permits the access of the heating medium to the under side of the billets, and 95 the formation of scale thereon. In this 100

type of furnace the scale covered sides are presented to the compression surfaces of both the upper and under rolls, and two sides instead of one of the rolled metal become embedded with the scale, aggravating the difficulties already pointed out.

I utilize the fact that two parallel sides of the billet are comparatively free from scale and I avoid the disadvantages already noted incident to the commonly practised method of rolling billets by the introduction of a billet ejecting mechanism which engages the end of the billet farthest from the rolls, and by a quarter turn brings the scale-free sides of the billet against the upper and lower surfaces of the roll passes, while the scale covered side or sides contacts with the sides of the roll passes, so that by the compression of the billet a coating of scale will become buckled and will fall off the billet by its own weight, allowing the billet to be turned, if desired, between each succeeding pair of rolls, and the rolling process completed without any interference from the accumulated scale.

Referring to the embodiment of my invention illustrated by way of example in the accompanying drawings, 1 denotes a billet heating furnace upon the floor 2 of which are a series of billets 3 lying side by side in the well known manner, with their vertical walls in contact. The billets are fed forward toward the delivery end of the furnace as each successive billet is introduced by any suitable pushing mechanism, in the present instance by a hydraulic pusher 4.

At the delivery end of the furnace the billets are fed out by an endwise movement through an aperture 5 in the side wall of the furnace into a stand of reducing rolls 6, by means of a reciprocating pushing bar 7. The bar 7 is moved back and forth by a pair of revolving pinch rolls 8 and 9 driven by a reversible motor 10. The push bar 7 is rectangular in cross section, and the rolls 8 and 9 bear with sufficient friction upon the upper and lower sides of the push bar to give a reciprocating motion to the latter. The forward end of the bar 7 is bifurcated, as shown in Fig. 3, the lower jaw 11 being beveled upon its upper and under surfaces to facilitate its insertion beneath the end of the billet. The upper prong 12 engages the upper surfaces of the billet with sufficient accuracy to cause the latter to be rotated as the bar 7 is turned. The advancing end of the bar 7 is slidably held in a framework 13, 13, supported upon a sprinkler pipe 14 carried upon the lower end of a water supply pipe 15, which is capable of a slight swinging movement in order to allow a lateral movement to be imparted to the advancing end of the pushing bar 7 to bring it in alinement with the

billet to be engaged. The pushing bar 7 besides being supported by the frame 13, 13, rests in a trough 16 pivoted at 17 upon a bracket 18 attached to the standard 19. The rear end of the trough 16 is provided on its sides with cheeks 20, 20, which tends to center the pushing bar 7 in the trough 16, when in its retracted position, and also to cause the swinging movement of the trough in a horizontal plane to be imparted to the push bar 7. The extreme rear end of the trough 16 is also capable of a lateral swinging movement by means of a flexible connection 21 with an overhead support. Said lateral swinging movement is imparted to the trough 16 as desired, by means of a handle 22. As the forked end of the push bar 7 approaches the furnace it is entered through an opening 23 and brought into alinement with the end of the billet to be fed forward. To facilitate the engagement of the prong 11 of the push bar with the under side of the billet, the floor or hearth 2 is cut away upon an incline which is protected by a water cooled plate 24, and the end of the billet is allowed to project slightly over the highest edge of the water cooled plate 24, so the prong 11 will slide upon the plate and engage the under side of the billet. As the push bar and billet are moved forward by the action of the pinch rolls 8 and 9, the push bar is turned one quarter revolution by providing a twisted section 25, Fig. 2, in the push bar. The pinch rolls 8 and 9 therefore, advance the bar 7 against the billet, but they also serve to rotate it one quarter turn as the twisted section 25 approaches the rolls. The rolls in the present instance are provided with two grooves. The billets are fed forward until the advancing billet is brought substantially in alinement with one or the other of the passes in the rolls. Considerable latitude is, however, possible in the manipulation of the billets by means of the lateral swinging movement of the push bar.

I claim,

1. In a billet handling device for rolling mills, a push bar having parallel surfaces on opposite sides, a pair of rotatable pinch rolls in frictional contact with the parallel surfaces of said push bar and means for rotating said rolls to impart a longitudinal movement to said push bar, said push bar having a quarter twist, whereby said push bar is rotated a quarter turn as it passes between said pinch rolls.

2. In a billet handling device for rolling mills, a push bar having parallel surfaces on opposite sides, a pair of rotatable pinch rolls in frictional contact with the parallel surfaces of said push bar, said push bar having a quarter twist, whereby said push bar is rotated a quarter turn as it passes be-

- tween said pinch rolls, and means for rotating said pinch rolls with a reverse motion.
3. In a billet handling device for rolling mills, a push bar provided with a quarter twist and having at one end means for engaging a billet upon its upper and lower sides only, a pair of rotatable forwarding rolls in frictional contact with the upper and lower surfaces of said push bar, and means for rotating said rolls to impart a longitudinal movement to said push bar, whereby said push bar is rotated a quarter turn as it passes between said rolls.
- 15 4. In a billet handling device for rolling mills, a heating furnace, means for feeding a row of billets in contact with each other, by a broadside step-by-step movement from one end of the furnace into alinement with a delivery opening in the side wall of the furnace, a pair of reducing rolls opposite said opening, means for pushing the billets by an endwise movement from the furnace into said reducing rolls, and means 25 for imparting to each billet a predetermined rotative movement of ninety degrees between the beginning of its endwise movement and its entrance between said reducing rolls.
- 30 5. In a billet handling device for rolling mills, the combination with a heating furnace having openings in its side walls, and a feeding mechanism for feeding billets in a continuous row from one end of the furnace to said side openings with their vertical side walls in contact, of a push bar having a bifurcated end adapted to engage the upper and under surfaces only of the end of a billet, means for imparting a reciprocating motion to said push bar to eject the billet from the furnace, and means for imparting a predetermined rotative movement to said push bar after the engagement of the push bar with the billet and before 45 the billet is ejected from the furnace.
6. In a billet handling device for rolling mills, the combination with a heating furnace, of a push bar provided at one end with means for engaging the end of a billet as 50 the latter is supported in the furnace, means for imparting a longitudinal movement to the push bar to eject a billet from the furnace, means to impart a rotative movement of ninety degrees to the push bar between 55 its engagement with the billet and the end of its longitudinal movement, and means for reversing the movement of the push bar.
7. In a billet handling device for rolling mills, a furnace having opposite openings in its side walls, a support for a row of billets with their vertical sides in contact, a push bar provided with means for engaging a billet, means for moving said bar lengthwise through one of said side openings, an inclined plate beneath the overhanging end 65 of the billets for supporting and raising the advancing end of said push bar and directing it into engagement with the end of a billet, and means for rotating said push bar ninety degrees at a predetermined period 70 in its longitudinal movement.
8. In a billet handling device for rolling mills, the combination with a heating furnace, of a push bar provided at one end with means for engaging the end of a billet as the latter is supported in the furnace, means for imparting a longitudinal movement to the push bar to eject a billet from the furnace, means to impart a rotative movement of ninety degrees to the push bar simultaneous with its longitudinal movement, means for reversing the longitudinal movement of the push bar, and means for applying a cooling medium to the billet engaging end of the push bar at the end of the reverse movement of the push bar.
9. In a billet handling device for rolling mills, a pivotally supported trough to swing in a horizontal plane, a reciprocating push bar held in said trough, and cheeks in said trough for centering said bar when in its retracted position.
10. In a billet handling device for rolling mills, the combination with a heating furnace having opposing openings in its side walls, of a trough pivotally supported at the side of the furnace to swing in a horizontal plane, a push bar held in said trough, means for imparting a longitudinal movement to said bar in said trough at one end of said trough, means for imparting a rotative movement to said bar of ninety degrees simultaneous with its longitudinal movement, means for reversing the longitudinal and rotative movements of said bar, 105 said bar moving means comprising a pair of pinch rolls engaging parallel surfaces of the push bar.

Dated this 23rd day of June 1917.
